UNITED STATES PATENT OFFICE.

IRA ROBBINS, OF PHILADELPHIA, PENNSYLVANIA.

ENVELOP-SEALING AND STAMP-AFFIXING MACHINE.

No. 893,546.

Specification of Letters Patent.

Patented July 14, 1908.

Application filed September 1, 1906. Serial No. 332,968.

To all whom it may concern:

Be it known that I, IRA ROBBINS, a citizen of the United States, residing in the city and county of Philadelphia, State of Pennsylvania, have invented a new and useful Improvement in Envelop-Sealing and Stamp-Affixing Machines, of which the following is a specification.

My present invention in its entirety consists of a novel and useful construction of an envelop sealing and stamp affixing machine by means of which the envelops passing through the machine are automatically sealed, stamped and passed out of the machine in an efficient and reliable manner.

It further consists of novel means for adjusting the envelops when they are initially placed in or on the machine.

It further consists of a novel construction of an envelop feeding device and novel means for actuating the same and accurately guiding the envelops to the feed rollers.

It further consists of a novel construction of feeding fingers or members carried by the envelop supporting table or slide, which engage the flap of an envelop to move the same into engagement with the feeding rollers.

It further consists of a novel construction of a moistening device by means of which only the flap of the envelop will be moistened and the envelop advanced to suitable flap bending and feeding members before the envelops pass between the sealing rollers provided therefor.

It further consists of novel means for maintaining each envelop in a stationary position during a predetermined interval before the same passes into engagement with the moistening rollers.

It further consists of a novel construction of a flap opening mechanism and novel means for actuating the same.

It further consists of a novel construction of a container adapted to hold a suitable liquid and a novel construction adapted to raise said container in order that the same will be in the path of the portion of one of the moistening rollers which engages the flap of the envelop.

It further consists of a novel construction by means of which the flap of the envelop is deflected so that when the envelops pass between the feeding rollers the flap will be in the proper position to be sealed.

It further consists of a novel construction

of feeding mechanism by means of which the envelops are fed to the sealing rolls.

It further consists of a novel construction of moistening device which is adapted to engage the portion of the envelop on which the stamp is to be placed and novel means for causing the moistening device to engage only the portion of the envelop which is to be stamped.

It further consists of a novel construction of a stamping mechanism and novel means for intermittently actuating the same.

It further consists of a novel construction of advancing mechanism by the employment of which the placing of the envelops in an accurate position to be stamped is positively assured.

It further consists of a novel construction of stamp - feeding mechanism and novel means for rendering the same inoperative when desired.

It further consists of novel means for removing an envelop from the machine after the same has been sealed and stamped.

It further consists of novel means for arranging and correlating the envelop feeding mechanism, the flap opening mechanism, the moistening mechanism, the flap bending device, the sealing rollers, the stamp moistening device, the stamping mechanism, the envelop discharging mechanism and their adjuncts, whereby when the machine is in operation, the different operations hereinbefore mentioned are simultaneously carried out.

It further consists of novel means for adjusting the different mechanisms whereby the different operations are carried out at a predetermined time with respect to each other.

It further consists of other novel features of construction all as will be hereinafter fully set forth.

In order to illustrate my invention, I have shown one form thereof which has been found in practice to give satisfactory and reliable results, although, it is obvious that the various instrumentalities of which my invention consists may be variously arranged and organized and it is not limited to the arrangement and organization as herein shown.

Figure 1 represents a front elevation of an envelop sealing and stamp affixing device embodying my invention. Fig. 2 represents a rear elevation thereof. Fig. 3 represents a

top plan view thereof. Fig. 4 represents a side elevation thereof. Fig. 5 represents a side elevation thereof showing the side opposite to that seen in Fig. 4. Fig. 6 represents a sectional elevation partly broken away of a portion of Fig. 5. Fig. 7 represents a side elevation showing more clearly certain of the parts seen in Fig. 6. Fig. 8 represents a section on line $x-x$ Fig. 6. Fig. 9 represents a sectional view of a portion of the machine showing the stamp feeding mechanism for the envelopes and the manner in which the stamps are brought into operative position with respect to the envelopes. Fig. 10 represents a plan view of a portion of the machine showing the manner in which the flap of the envelop is opened. Fig. 11 represents a sectional view of a portion of the machine showing more clearly the means for feeding an envelop to the moistening rollers. Fig. 12 represents a sectional view of the moistening rollers and showing in addition the means for holding an envelop so that only the flap thereof is moistened. Fig. 13 represents a sectional view of a portion of the machine showing the manner in which the flap of an envelop is opened before it passes to the moistening rollers. Fig. 14 represents a sectional view similar to Fig. 13 but showing the parts in a different relation to each other. Fig. 15 represents a sectional view of a portion of the machine showing the means for deflecting the flap of an envelop before the same passes to the sealing rollers. Fig. 16 represents a sectional view similar to Fig. 15 but showing the parts in the position they assume at a different point in the operation and showing also a portion of the sealing rollers. Fig. 17 represents, in side elevation, a portion of Fig. 11 showing the parts in a different relation to each other. Fig. 18 represents a side elevation of one of the envelop guide members employed.

Similar numerals of reference indicate corresponding parts in the figures.

Referring to the drawings, in the detailed description of my novel sealing and stamp affixing machine, it will be understood that I have shown but one embodiment of the broad principle of my invention, since it is apparent that the same may be carried out in various forms of mechanisms or organizations without departing from the spirit of my invention.

The present invention in its entirety comprises several distinct sets of mechanism which coöperate and are dependent upon each other to produce the ultimate objects or results sought for and I will therefore describe each of the same in detail and in the natural or logical sequence in which they are thrown into operation.

The frame of the machine will vary in accordance with the size and weight of the machine and in the present instance comprises

two side members 1 and 2 which are suitably secured with respect to each other by means of cross rods or bars 3.

4 designates the driving shaft which is suitably journaled in the sides 1 and 2, the improper movement of said shaft being prevented by means of a set collar 5 and other members to which reference will hereinafter be made.

The envelop-feeding mechanism.—I will first describe the construction employed for feeding the envelopes into the machine.

6 designates a gear mounted on the driving shaft 4 and having pivoted thereto at 7 one end of a connecting rod 8 which is connected at its opposite end by means of a pin, bolt or equivalent device 9 to an arm 10 carried by a shaft 11 suitably journaled in the sides 1 and 2. The arm 10 is provided with a slot or groove 12 in order that the connecting arm 8 may be adjustably secured to the arm 10.

13 designates a set screw by means of which the arm 10 is adjustably secured to the shaft 11.

14 designates an arm adjustably mounted on the shaft 11 by means of a set screw 15, the outer end of said arm or lever 14 having pivoted thereto at 16 a roller 17 which engages the arms or fork 18 depending from the sliding feed table or envelop support 19 which latter is movably mounted on plates 20 carried by the side members 1 and 2 in any suitable manner. The plates 20 are provided at their inner edges with grooves or ways 21 with which the feed member 19 engages. As most clearly seen in Figs. 11 and 17, the ways 21 are partly cut away at their rear, as seen at 22, and are provided with an inclined or cam face 23 with which is adapted to coat the cam face 24 of the under side of the block or weighted end 25 of the lever 26 which is pivoted at 27 to the feed table 19, it being noted that two of these levers are employed and that the feed table 19 is recessed or apertured as at 28, so that said levers 26 may extend therethrough.

29 designates set screws engaging the levers 26 by means of which the same may be adjusted.

30 designates supporting members secured at one end to the levers 26 and having their free ends deflected upwardly to a desired degree so that said ends are in a plane above the flanges 31 of the plates 20. The flanges 31 are cut away or recessed at their forward end as seen most clearly at 32 in Figs. 11 and 17. The machine is regulated for envelopes of different widths by adjusting the guide members 33 which are provided with slots 34, whereby said members may be adjustably secured to the plates 20 by means of bolts or equivalent devices 35 passing through the slots 34 and engaging said plate.

The machine is regulated for envelopes of

different lengths by means of a guide member 36 adjustably secured to a plate 20 on one side of the machine by means of a bolt 37 passing through a laterally extending slot 38 in the plate, 20 and by means of a guide member 39 adjustably carried on the other plate 20 by means of a bolt 40 which passes through a slot 41 in said latter plate, it being understood that the bolts 37 and 40 are provided with suitable nuts.

42 designates a gear mounted on a shaft 43 journaled in boxes 44 movably mounted in the sides 1 and 2 of the frame, as will herein-after more fully appear in connection with the envelop sealing mechanism. The gear 42 meshes with a gear 45 mounted on a shaft 46 suitably journaled in the side chambers 1 and 2. The gear 45 meshes with a gear 47 mounted on a shaft 48, and said gear 47 meshes with a gear 49 mounted on a shaft 50, which latter is journaled in boxes 51 as most clearly seen in Fig. 4.

The boxes 51 are mounted in vertical guides or ways 52, said boxes being maintained in their lowermost position by means of springs 53, encircling the pins or rods 54 and interposed between said boxes and the caps or plates 55 which are removably secured in any suitable manner to the sides of the machine frame.

In the present instance, I employ a plurality of feed rollers 56 adjustably mounted on the shaft 48 with which coact feed rollers 57 adjustably mounted on the shaft 50, it being now apparent that owing to the provision of the springs 53, the feed rollers 57 yieldingly engage the feed rollers 56.

58 designates a gear mounted on the shaft 46 and engaging a gear 59 mounted on a shaft 60 suitably journaled in or carried by the side members 1 and 2 of the machine frame.

61 designates feed rollers adjustably mounted on the shaft 60, as seen in Figs. 3 and 4, and engaging feed rollers 62 which are pivoted at the outer ends of the arms or brackets 63 whose opposite ends are loosely mounted on the shaft 50 and owing to the provision of set collars 64 adjustably mounted on the shaft 50, any improper lateral movement of said brackets or the feed rollers 62 is positively prevented and owing to the manner in which they are mounted their weight will cause them to engage with the coacting feed rollers 61, as is apparent.

65 designates a rod or shaft carried by the side members of the frame and having adjustably secured thereon brackets or guide members 66 which are provided with slots, as seen at 67 in Fig. 2, in which are movably mounted plates or bars 68 having slots 69 through which pass pins 70, which latter engage the members 66. The weight of the members 68 causes them to normally assume

their lowermost position and since they are cut away or recessed, as seen at 71 in Fig. 11, provision is made for their vertical movement in the same vertical plane as said rod 65.

72 designates pawls pivoted to the members 68, the rearward movement of which is limited by stops 73, as clearly seen in Figs. 11 and 17. The pawls 72 have at their upper end pins or lugs 74 with which engage the free ends of springs 75 carried by blocks 76 which latter are adjustably secured to the plates 68 by means of set screws or equivalent devices 77. The pawls 72 are in alignment with the flanges 31 so that a space is left between the lower ends of said pawls and the upper face of said flanges.

The height of the pawls above the flanges 31 is regulated by adjusting the set screws 78 carried by the plates or bars 68 and abutting against a suitable fixed portion of the machine and in the present instance they are shown as abutting against the top of the brackets 66.

The mechanism for directing the envelops to the flap moistening device.—As seen most clearly in Fig. 5, 79 designates a gear meshing with the driving gear 6 and mounted on a shaft 80 suitably journaled in the side members 1 and 2.

81 designates a cam member mounted on the shaft 80 and having two similar cam faces 82 thereon which coact with a roller 83 pivoted to an arm or bracket 84 which is adjustably mounted on a shaft 85 suitably journaled in the side members 1 and 2 by means of a set screw 86. The roller 83 is maintained in engagement with the cam 81 by means of a spring 87, one end of which is secured to the bracket 84 and the other end thereof to a pin, lug or suitably fixed point 88 on the side member 2 of the frame.

89 designates guide members preferably grooved and adjustably mounted in any suitable manner on the rock shaft 85, it being noted that these guide members are so located with respect to the feed rollers 61 and 62 that they receive an envelop after it leaves said feed rollers.

90 designates a rod or bar carried by the side members 1 and 2 and having adjustably secured thereon a guide plate or member 91 which guides the envelop which is now passed to the moistening rollers 92 and 93. The roller 92 is mounted on the driving shaft 4 and is provided at each end with flanges 94. The roller 93 is mounted on the shaft 43 and is provided at each end with flanges 95 having a portion of their circumference cut away, as seen at 96.

97 designates a rod or bar rotatably mounted in any suitable manner in the machine and having adjustably mounted in any suitable manner thereon the arms 98 provided at their lower ends with the hooks or

catches 99. One of the arms 98 has its rear face cut away, as seen at 100, thus forming a shoulder 101.

102 designates a cam block mounted on the 5 shaft 43 and having a top face 103 and release face 104 with which the said arm 98 having the cut away portion 100 and shoulder 101 coacts.

124 designates a preferably metallic plate 10 secured to the roller 92 in any suitable manner, as seen most clearly in Fig. 1. The opposite roller 93 which is mounted on the shaft 43 is provided with a pad 125 which is secured to the roller 93 in any suitable manner 15 and in the present instance I have shown this as being accomplished by means of the bar 126 provided with screws 127 which pass through the bar 126 and the member 125 and engage the roller 93.

20 128 designates bars or members loosely mounted at one end on the shaft or bar 11 and provided at their opposite ends with suitable actuating handles, as seen most clearly in Fig. 5. The bars 128 have extended laterally therefrom the arms 129 on which is adjustably mounted blocks 130 to which the guiding plate or members 131 are secured in any suitable manner. The bars 128 are recessed on their inner face as seen at 30 131* in Fig. 3, in order to support a liquid container 132 which is adapted to contain any suitable or moistening material therein.

133 designates a plate as most clearly seen in Fig. 1 having secured on its upper face an 35 absorbent pad 134 made of any suitable material with which the plate 124 engages when the side members 128 are in raised position. The vertical adjustment of said side members 128 and the liquid container 40 132 carried thereby is accomplished in the following manner:—The rod or shaft 135 is provided with an operating handle 136 and is suitably journaled in the sides 1 and 2 of the frame. Mounted on the shaft 135 are cam 45 blocks 137 having differential diameters 138 and 139 and as seen most clearly in Fig. 5 the diameter 139 is cut away, as seen at 140 in said figure. The side bars 128 are provided with depending arms or lugs 141 which engage the diameter 139 of the cam blocks 137, so that when said handle 136 is actuated the shaft 135 will be rotated and the container raised or lowered as desired, as will be readily apparent from the drawings.

55 *The mechanism for opening the flap of the envelop.*—142 designates a casing adjustably carried on one of the cross rods 3 of the frame and having movably mounted therein a rod 143 provided with a block or enlargement 60 144 between which and the removable end or cap 145 is interposed a spring 146.

147 designates a slot in the upper face of the casing 142 through which passes a pin 148 which engages the enlargement or block 65 144.

149 designates lateral slots at the inner end of the casing 142 in which is movable a plate or bar 150 fixed to the block 144 or rod 143 in any suitable manner, it being apparent that owing to the provision of the slots 70 149 the plate or bar 150 is non-rotatably mounted.

151 designates a bracket carried by the side member 1 of the machine casing as seen in Fig. 1, and provided with an upwardly extending pin or lug 152 on which is rotatably mounted a sleeve 153 on which latter is adjustably mounted an arm 154 by means of a set screw or equivalent device 155, it being seen as indicated most clearly in Fig. 1 that 80 this arm is extended so as to engage the upwardly projecting pin 148 carried by the rod 143.

156 designates an arm also mounted on the sleeve 153 and provided at its outer end with a roller 156* which coacts with the cam face 157 of the cam block 158 which is adjustably secured by means of a set screw or equivalent device 159 to the driving shaft 4. 90

Mechanism for bending the flap of the envelop.—As seen in Fig. 5, 160 designates a rod or pin carried by the side member 2 of the machine frame having mounted thereon an elbow lever 161 to one end of which is pivoted a roller 162 which is adapted to coact with a cam 163 on a shaft 164 carried by the side member 2 of the frame, said shaft having mounted thereon a gear 165 which meshes with the gear 6 carried by the driving shaft 4. 100 The opposite end of the elbow lever 161 has pivoted thereto a roller 166 which engages the slot or groove 167 of an arm 168 adjustably mounted in any suitable manner on a rod or shaft 169, which latter is suitably 105 journaled in the side members 1 and 2 of the frame.

170 designates a lug or projection extending from the outer end of the elbow lever 161, having secured thereto one end of a spring 110 171, the other end of which is secured to a suitable fixed point 172 so as to cause the roller 162 to always engage the operative cam surface of the cam member 163 as will be readily apparent from Fig. 5. The shaft 115 169 has secured thereto a bracket 173 to which is secured in any suitable manner a plate or bar 174, it being understood that a similar bracket 175 is mounted on a rod or pin 176 carried by the side member 1 of the 120 frame and that one end of the plate or bar 174 is secured to said bracket 175.

177 designates laterally extending slots or apertures in the plate or bar 174, adapted to receive the forwardly extending plates or 125 members 178 provided with upwardly extending flanges 179 in which is journaled a rod 180 which is prevented from improper lateral movement by means of set collars 181.

182 designates blocks adjustably secured 130

in the longitudinally extending slots 183 in the plates 178. The blocks 182 have secured thereto and extending therefrom the guide rods or members 184, the outer ends of which are deflected upwardly in such a manner that the descending envelop owing to the provision of guide members 131 is directed to the members 178 as most clearly indicated in Fig. 15.

10 In order to rock the shaft 180, a block 185 is adjustably secured thereto, as indicated in Fig. 2, said block having a cam member 186 extending downwardly therefrom and adapted to engage a roller 187 mounted on a rod or pin 188 carried by the side member 1 of the frame. This cam member 186 is deflected at its lower end so that when the shaft 169 is rocked the engagement of this member 186 with the roller 187 will cause 20 the shaft 180 to be rocked and actuate a plate or bracket 189 adjustably mounted on the shaft 180.

The cam member 186 is normally held against the anti-friction roller 187 by the weight of the bracket 189 mounted on the bar 174. As this bar is rocked, the cam 186 is carried forward and backward and owing to its peculiar shape, its engagement with the anti-friction roller 187 causes the shaft 180 to 30 be rocked in such a manner that it operates with an exaggerated movement relative to the bar 174.

The member 189 has secured at its outer end a bracket 190 in which is pivoted at 191 35 a depending plate or member 192 which serves as a flap closing member.

Mechanism for feeding the envelops to the sealing rollers.—193 designates an elbow lever as most clearly seen in Fig. 5, said lever 40 being provided at one end with a roller 194 which engages a slot 195 in an arm 196 mounted in any suitable manner on a rock shaft 197 which is suitably journaled in the frame of the machine.

45 198 designates feeding arms or fingers adjustably secured by means of set screws 199 on the shaft 197.

200 designates a spring mounted on the shaft 197, as seen in Fig. 2, whereby the feeding members 198 carried thereby are normally maintained in their rearmost position at which time they engage the bar or plate 174 and the lever 193 is maintained in engagement with its actuating means. The bracket 189 is provided on its end face with the reversely inclined cam faces 201 and 202, which permit the member 189 to be readily rocked, it being understood as seen in Fig. 2 that the member 189 is located in the present instance directly above one of the plates or receiving members 178 so that as seen in Figs. 11, 15 and 16, the reversely inclined cam faces 201 and 202 will engage with said plate and serve as a stop to limit the movement of said bracket.

203 designates a roller carried at the outer end of the elbow lever 193 and adapted to coact with a cam member 204 mounted on a shaft 205 carried by the side member 2 of the frame. The shaft 205 has thereon a gear 260 which meshes with an idler 206 suitably journaled at 207. The idler 206 is driven by a gear 208 on a shaft 209, said gear 208 meshing with the gear 165 driven by the gear 6, as clearly indicated in Fig. 5. The shaft 209 has mounted thereon a feed roller 210 which coacts with a feed roller 211 mounted on a shaft 212 which latter is suitably journaled in boxes 213 which are movably mounted in the ways or guides 214.

215 designates springs interposed between the boxes 213 and the caps or bars 216 suitably secured to the frame whereby the roller 211 normally engages the roller 210.

217 designates a gear driven by the idler 206 and mounted on a shaft 218 to which is secured a feed roller 219.

220 designates a feed roller adapted to coact with the feed roller 219 and mounted on a shaft 221 which is journaled in boxes 222. The boxes 222 are mounted in the slots or grooves 223 and are maintained normally in raised position by means of springs 224 interposed between said boxes and the caps or plates 225 which are suitably secured to the machine frame.

Mechanism for moistening the stamp receiving portion of the envelop.—The envelop has now passed between the sealing rollers and is ready to be moistened and stamped.

226 designates a bracket or collar loosely mounted on the shaft 43 and having extending therefrom an arm 227 provided with a depending lug or cam 228 which coacts with a cam block 229 carried by the driving shaft 4, said cam block having a portion of its periphery cut away so that at a predetermined time the outer end 230 of said arm 227 will be lowered. The arm 227 is provided near its end with a slot or recess 231 adapting the same to receive a lever or link 232 which is provided with a slot 233 in order that it may be readily placed on the end of the lever 227. The lower end of the lever or arm 232 is provided at 234 with a plate or bar 235 which is pivoted at its outer end at 236 to the side member 1 as most clearly seen in Fig. 1 of the drawings. The opposite end of the arm 235 is provided with a slot 237 with which engages a pin 238 in order to accurately 115 guide the movement of said bar 235.

239 designates a rod, as most clearly seen in Fig. 5, which passes through the apertured flange 240 extending from the bar or plate 235. The rod also passes through an apertured angle piece 241 which is carried in any suitable manner by the frame of the machine and between which and the nut 242 carried by the rod or bolt 239 is interposed a spring 243. The bar 235 is provided with a 125

lateral slot 244, as seen in Fig. 1, through which passes fastening devices 245 which engage a plate 246, having extending thereto from set screws 247 which latter extend through the slot 244.

248 designates a liquid container provided with the slotted flanges 249 which are adapted to engage the screws or pins 247, as may be readily seen from Fig. 1. As indicated in Fig. 3, the container 248 has pivoted thereto at 250 a block or plate 251 from which extends an arm 252 through which passes a set screw 253 which engages the absorbent material 254* carried thereby, it being understood that this material extends into the chamber of the container 248. In order to securely and rigidly maintain this fastening device 253 mounted in the pivoted bracket 251, the arm 252 extending from this bracket is provided with a set screw 254 which engages a portion of the container and thus prevents any loosening of the fastening device 253. As seen in Fig. 5, 255 designates an angle arm extending rearwardly from the bottom of the machine frame and provided on its upwardly extending portion with guides 256 in which is movably mounted an upright or standard 257, the upper end of which terminates directly below the moistening or absorbing material 254*.

258 designates an arm one end of which terminates beneath the plate 257, the other end thereof being mounted on a rock shaft 259 to which reference will hereinafter be made in connection with the stamping mechanism.

261 designates an arm eccentrically secured to the gear 260 and loosely mounted on the shaft 205, said arm having pivoted to its outer end a casing or slotted arm 262 in which is adjustably secured a rack arm 263 by means of set screws 264. This rack arm 263 meshes with a pinion 265 loosely mounted on a shaft 266 suitably journaled in the machine frame. The pinion 265 has fixed thereto a block 267 to which is pivoted a pawl 268, the operative end of which is normally pressed outwardly by means of a spring 269 secured at one end to the block 267 and having its free end engaging one end of the pawl 268, so that the operative end thereof tends to move outwardly and engage the inner periphery 270 of the collar or sleeve 271 fixed on a shaft 266 in any suitable manner as indicated in Fig. 8. The inner periphery 270 of the sleeve 271 is provided with a shoulder 272 with which the pawl 268 engages during the operation to cause said collar or sleeve 271 and also the shaft 266 to which said collar is fixedly secured to rotate. A casing member 105 is loosely mounted on the shaft 266 and is provided with an aperture 106 through which the rack arm 263 passes and whereby said arm is maintained in operative relation with the pinion 265, it

being noted that the casing member 105 is adapted to extend over a portion of the collar or sleeve 271 and is maintained in proper relation with respect thereto by means of a set collar 107.

276 designates a gear mounted on the shaft 266 and meshing with a gear 277 mounted on a shaft 278 journaled in a table or support 279, which is movably mounted on a plate or bracket 280 which is carried by and forms part of the machine frame.

281 designates a depending arm extending from the table or support 280 and provided with a laterally extending slot 282.

283 designates an arm carried by the upper table or support 279 and provided with a set screw 284, which passes through the arm 283 and is provided at its inner end with a shoulder or nut whereby the table 279 is adjustably secured with respect to the table 280.

285 designates a pinion or gear mounted on the one end of the shaft 278 and meshing with a pinion or gear 286 mounted on a shaft 287 suitably journaled at one end in a lug or bracket 288 which is carried by the table 279.

The opposite end of the feed roller 287 is journaled in an arm 289 pivoted at 290 to the table 279 and having pivoted at its free end a lever 291 provided at its lower end with a cam face 108 so that when said lever is actuated the enlarged diameter 293 of the feed roller 287 will be raised, so that the stamps which are guided in the groove member or guide 294 may be passed under said enlarged diameter 293 of the feed roller 287.

In order to maintain the lever 291 in the adjusted position given thereto, I provide a spring 295 which is pivoted at one end at a suitable point to the table 279, its free end engaging the pivot pin 292 on which the lever 291 is mounted.

296 designates a spring secured at one end to the table 279, the other or free end thereof being in alignment with the stamp guide 294, so that as the stamps pass between the feed members 287 and 278, any deflection or improper movement is positively prevented. The spring 296 exerts a yielding pressure on the stamps which are being fed, so that the stamp next to the stamp which is being severed will not be advanced during the severing operation.

297 designates brackets carried by the table 279 in which are journaled the rods 298 and 299, said rods having secured thereto in any suitable manner, a block 300 to which is adjustably secured a depending arm 301 which engages a cam block 302 adjustably mounted on the shaft 266, said cam block having the release face 303, whereby the rods 298 and 299 are rocked to effect the stamping of the envelop as will be hereinafter described.

304 designates a knife member pivoted on the rod 299 and having secured thereto a

bracket 305 in which is carried a rod 306, which is adjustably secured thereto by means of lock nuts 307.

308 designates a presser piece pivotally carried by the rod 306 and having a guide pin 309 which engages the side of the knife member 304.

In order to insure the envelops being placed in proper position upon the stamp bed 310 of the machine which may, if desired, be formed of a continuation of the table or support 279, I mount on the shaft 266 a cam block 311 provided with a release face 312, which co-acts with a lever or cam member 313 adjustably mounted on a rod 314 journaled in a bracket 315 carried by the machine in any suitable manner as most clearly indicated in Fig. 3.

316 designates a set collar adjustably mounted on the rod 314 between which and a fixed point on a bracket 315 is interposed a spring 317, whereby the lever or cam member 313 is always maintained in engagement with the cam block 311.

25 The end of the rod 314 has adjustably secured thereto a rod 318 which is secured at one end of a lever 319 fulcrumed at 320 to a suitable fixed point of the machine frame.

The lever 319 has secured at its outer end 30 an upwardly extending arm 321, the upper end of which is serrated and deflected rearwardly as most clearly seen in Fig. 3 in dotted lines and also Fig. 9, so that the passage of the envelop from the feeding rollers 219 and 220 to the proper position on the plate or bed 310 is assured, it being noted that a guide member 322 is pivoted at one end to the bed 280, the outer or free end of said guide 322 being deflected upwardly as 40 clearly indicated in the drawings, it being also noted that the forward movement of the envelop is limited by the table 279.

323 designates a roller mounted in a bracket 324 preferably carried by the stamp guide member 294, as seen in Fig. 9, whereby the strips of stamps may be wound on said roller 323 if desired and passed through or over a guide 325 and thereby to the feeding rollers for the stamp, as clearly indicated in 50 said Fig. 9.

Mechanism for removing the stamped envelops from the bed.—326 designates a cam block mounted on a sleeve 327 carried by the shaft 266, it being noted that the cam member 326 is provided with a release face 328 with which a cam member 329 co-acts, said member being mounted on a shaft 330 carried by an arm 331 carried by any suitable portion of the machine frame. The shaft 60 330 has mounted thereon, a lever arm 332, the upper end of which is deflected, as clearly seen in Figs. 1 and 4 of the drawings. The shaft 330 is provided with a torsional spring 333, whereby the cam member 329 is maintained in engagement with the cam member

326, as indicated in Fig. 1 of the drawings, it being seen in Fig. 3 that the bed 310 is suitably cut away or recessed as seen at 334, in order to provide for the movement of said lever. 70

335 designates a plate carried by the depending arm 283 which engages a groove 336 in a set collar 337 keyed on the sleeve 327, as clearly indicated in Fig. 1.

The operation of the machine will now be 75 readily apparent to those skilled in this art. I will first describe the manner in which the envelops are fed into the machine.

The envelops which are to be sealed and stamped are placed in position upon the sliding table 19 between the guide members 36 and 39 and owing to the provision of the cam face 338 on the under side of the guide 39, said guide may be bent rearwardly toward the side of the machine, so that the envelops 80 may be the more readily placed in proper position for being fed into the machine, as most clearly indicated in Fig. 18, it being noted that the guides 36 and 39 serve for the lateral adjustment of the envelops and the guide 90 members 33 serve for the longitudinal adjustment of the envelops. In the present instance, I have shown the driving shaft 4 as being provided with a handle 339, whereby the same may be manually actuated, although it is to be understood that in the broad scope of my invention, it is immaterial in what manner the driving shaft is driven and the same may be actuated either manually as shown or by means of any suitable or conventional type of motor or driving mechanism, as will be readily apparent. On the rotation of the driving shaft 4, the gear 6 carried thereby, owing to the provision of the crank arm 8 and the manner in which it is secured to said gear, will cause the shaft 11 to be rocked forwardly, it being noted that the connecting arm 8 is adjustably secured in the slot 12 of the link 10 which latter is secured to the shaft 11. Since the shaft 11 has 100 secured thereto the arms 14 which carry at their outer end the roller 17 engaging the arms or fork 18 depending from the envelop feed table or member 19, the latter will be carried forwardly as the shaft 11 is rocked. 105

The envelops normally rest on the flanges 31 of the table 19 and the feeding fingers or members 30, and owing to the manner in which the flanges 31 are cut away, as seen at 110 32 in Figs. 11 and 17, the flap of the lowermost envelop will assume the position as indicated in said Fig. 11, it being understood that the envelops when placed in position are placed one above the other with the flap portion of the envelop underneath and with 115 the flap of the envelops nearest to the feeding rollers. As the table 19 moves forwardly, the lever arms 26 pivoted thereto owing to the cam face 24 on the weighted end 25 of said lever and inclined cam face 23 on the 120 130

ways 21, the ends of the levers 26 to which the feeding members 30 are secured will cause the ends of said members to move downwardly, so that the envelop will pass between the lower ends of the pawl 72 and the top face of the flanges 31, it being noted that owing to the manner in which these pawls are pivoted and the tension device therefor, that if an envelop is being fed which 10 has a greater thickness than an ordinary envelop, these spring actuated pawls will turn on their pivot and permit the envelop to pass between the lower ends of the same and the top of said flanges 31, whereby the lower envelop, which is now being fed forwardly by 15 the engagement of the members 30 with the flap thereof, will pass in an accurate manner to the feed rollers 56 and 57.

As most clearly indicated in Fig. 5, the 20 driving gear 6 actuates the gear 42, which in turn actuates the gear 45 which meshes with the gear 47 mounted on the shaft in which the lower feed roller is secured, said gear 47 meshing with the gear 49 mounted on the 25 upper shaft 50 to which the upper feed roller 57 is secured, so that the advancing envelop passes between the feed rollers 61 and 62, as will be apparent from the drawings. The feed roller 61 is mounted on a shaft 59 on 30 which latter is also mounted a gear 60 which meshes with a gear 58 carried by the shaft 46. The envelop after passing from the rollers 61 and 62 falls on the guide members 89 mounted on the rock shaft 85. The driving gear 6 35 meshes with the gear 79 mounted on the shaft 80 on which is also mounted the cam member 81 with which coacts the roller 83 carried by the bracket 84 and secured to the shaft 85 on which the guide members 89 are 40 mounted, so that as the shaft 80 rotates in unison with the rotation of the driving shaft 4, the guide members 89 will be rocked and the envelop supported thereon will slide from said guiding members and engaging the guide 45 plate 91 will be deflected downwardly as indicated in Fig. 11 towards the moistening device for the flap of the envelop. At this time, owing to the provision of the cam member 102 and the construction of the arm 98 50 coacting therewith, the hooks or catches 99 will at this time be in the position indicated in Fig. 12 and the descending envelop will be received thereon as clearly indicated in said figure.

55 As indicated most clearly in Fig. 5, the shaft 43 is rotated by means of the gear 42 meshing with the drive gear 6 and owing to the provision of the cam member 102 and the manner in which its operative surface is cut away, as this shaft rotates, the arm 98 coacting with said cam will be moved quickly rearwardly so that the envelop may descend and be engaged by the flanges 94 and 95 of the moistening and feed rollers 92 and 93 and 60 fed downwardly thereby.

Means for opening the flap of the envelop.—The flap of the envelop is now opened in the following manner:—As seen most clearly in Figs. 1, 10, and 3, the cam block 158 is mounted on the driving shaft 4 and rotates 70 in unison therewith. The operative cam surface 157 on the side of said cam block coacts with the roller 156^x carried by the arm 156 which is secured to the sleeve 153, mounted on the rod 152. As clearly indicated in the 75 drawings, the arm 154 engages the pin 148 and normally maintains the plate 150 in its rearmost position. As the shaft 4 rotates the cam member 158 will permit said arm 154 to turn on its pivot and owing to the 80 provision of the spring 146 the plate 150 will be moved forwardly and engage the envelop, as most clearly indicated in Fig. 10. The envelop is now being fed downwardly between the moistening rollers and owing 85 to the position of the plate or blade 150 the flap of the envelop will be opened, as most clearly indicated in Fig. 14. It is, of course, to be understood that before the machine is set in operation the handle 136 90 is actuated to rotate the shaft 135 and owing to the provision of the cam blocks 140 which coact with the depending members 139 carried by the arms 128, said arms will be raised, as indicated most clearly in Fig. 1. 95 This will bring the pad of absorbent material 134 located within the container 133 in the path of the plate 124 so that said plate 124 will be suitably moistened thereby. Owing to the provision of the pad 125 the flap of the 100 envelop will be pressed against the plate 124 and be moistened thereby as the envelop is being fed downwardly by the engagement of the flanges of the rollers 92 and 93 therewith. As the envelop passes from the moistening 105 rollers 92 and 93, it is guided by the members 131 so that the same passes between the arms 184 and the plates 178, as most clearly indicated in Fig. 15, it being understood that the parts are now in the position as indicated in 110 said figure.

Means for bending the flap of the envelop before it passes to the sealing rollers.—The gear 6 mounted on the driving shaft 4 coacts with the gear 165 mounted on the shaft 164 on 115 which is also mounted the cam member 163 with which the roller 162 is maintained in engagement by means of the spring 171 secured at the outer end of the elbow lever 161 on which said roller is mounted. The roller 166 carried by the elbow lever 161 and engaging the groove 167 in the arm 168 will cause the shaft 169 on which it is mounted to be rocked forwardly. As the shaft 169 is rocked, the shaft 170 will also be rocked owing to the provision 120 of the cam member 186 adjustably carried by the block 185 and since this member is deflected downwardly as the same moves on the roller 187 journaled at 188 it will cause the said shaft 180 to be rocked forwardly and 130

the bracket 189 carried thereby will be moved downwardly, as indicated most clearly in Fig. 16, it being noted that owing to the provision of the cam faces 201 and 202 this movement is permitted and the cam face 201 will limit the rearward movement of said bracket 189. The plate 192 which is pivoted at 191 on the bracket 190 will be carried downwardly by the arm or bracket 189 and owing to the location of this pivoted member it will engage the flap of the envelop, as clearly indicated in Fig. 16 and cause the same to be deflected downwardly.

Means for feeding the envelops to the sealing rollers.—The envelop is now fed between the sealing rollers. Referring to Figs. 1 and 5, it will be seen that owing to the provision of the roller 203 coacting with the cam 204 carried by the shaft 205 and the roller 194 carried by said lever 193 and engaging the slot 195 in the arm 196, the shaft 197 will be rocked forwardly and thus cause the arms 198 to turn on their fulcrum 197 and the envelop will be moved forwardly into engagement with the sealing rollers 210 and 211, as most clearly indicated in Fig. 11, it being noted that owing to the manner in which the plate 192 is pivoted that this does not prevent in any manner the passage of the envelop to the sealing rollers. The envelop passes from the sealing rollers 210 and 211 to the second set of sealing rollers 219 and 220 which latter are driven by means of the idler 206 which meshes with the gear 208 mounted on the shaft 209, said gear 208 meshing with the gear 165 driven by the gear 6, as may be clearly understood from Fig. 5.

Means for moistening the stamp receiving portion of the envelop.—As seen in Fig. 2, the collar or bracket 226 is mounted on the shaft 43 and this collar has extending therefrom an arm 227, as seen in Fig. 3, provided with a depending lug or cam 228 which coacts with the cam block 229 carried by the driving shaft 4, so that as said cam is rotated the arm 227 will be lowered and raised at a predetermined time. The lever arm 235 which is pivoted at one end, as at 236, to a fixed portion of the frame, is operatively connected by means of the link 232 with the end 230 of the lever 227, it being noted that owing to the provision of the slot 233 in said link 232 and the recess 231 on the lever 227 that this link may be readily disengaged when desired. As the envelop passes beneath the stamp moistening device 248, the same is lowered owing to the provision of the cam or lug 228 and the coacting cam block 229 mounted on the shaft 4, so that the absorbent or other material 254^x engages that portion of the envelop on which the stamp is to be placed.

Referring now to Fig. 5, it will be seen that the driving gear 6 meshes with the gear 165, which in turn meshes with the gear 208, which drives the idler 206, which latter meshes with

the gear 260 to which the bracket or casing 262 is eccentrically secured so that the rack arm 263 is reciprocated. The rack arm 263 coacts with the pinion 265 to which latter is secured the member 267 which carries the pawl 268 and owing to the provision of the shoulder 272 on the inner periphery of the collar or sleeve 271 it will be understood that as the rack arm travels forwardly the shaft 266 does not rotate since the pawl 268 moves freely within the collar or sleeve 271. On the further rotation of the gear 260 it will be apparent that the arm 263 will begin to move rearwardly and as this rack arm moves rearwardly and rotates the pinion 265 the pawl 268 will engage the shoulder 272 of the collar or sleeve 271 and since this sleeve is fixed to the said shaft 266 this shaft will be caused to rotate. As the shaft 266 rotates the cam block 273 will rotate in unison therewith and as the cam block coacts with the roller 274 carried by the bracket 275 secured to the shaft 259, said shaft will be rocked, as is apparent from Figs. 1 and 4. This will cause the arm 258 to be raised and engage the lower end of the plate 257 and cause said plate to be moved upwardly so that the envelop will be pressed against the absorbent or other material 254^x carried by the moistening device 248.

Means for passing the envelop from the feed rollers into position to be stamped.—The envelop is now passed from the feed rollers into position to be stamped. Owing to the provision of the cam block 311 having the release face 312 thereon and mounted on the shaft 266, as this release face passes beyond the arm or cam member 313, said member will be permitted to move rearwardly together with the rod 314 to which it is secured owing to the provision of the spring 317 interposed between said collar 316 and the fixed portion of the bracket 315, as most clearly indicated in Fig. 3. This will cause the lever 319 to operate the rod or pin 318 carried by the member 314 thus causing the serrated arm 321 carried by said lever 319 to move forwardly and thus move the envelop on to the table or support 310 and beneath the stamping device.

Means for feeding the stamps into proper position above the envelop.—The stamps are fed into the machine through or over the guide member 294, said stamps being preferably upon a suitable roller 323, as indicated in Fig. 9. The shaft 266 carries a gear 276 which meshes with a gear 277 mounted on a shaft 278, a portion of which forms the lower feed roller of the stamp feeding mechanism. The shaft 278 is provided with a pinion 285 which meshes with a pinion 286 carried by the upper feed member 287, which is provided in the present instance with an enlarged diameter 293, which coacts with the lower feed roller, so that as the shaft 266 is

rotated the feed members 278 and 287 will also be rotated so that the stamp is fed beneath the severing member 304 and the presser member 308. The envelop is now 5 in the proper position to be stamped and the stamp therefor is held in the proper position above the envelop.

Means for stamping the envelop.—The shaft 266 has mounted thereon the cam block 302 which has on its side face an operative cam surface with which the lever or arm 301 coacts, said latter arm or lever being carried by the bracket 300. The bracket 300 has secured thereto the rods or shafts 298 and 15 299, so that as the depending arm 301 engages the release face 303 of the cam block 302, said shaft will be rocked, it being noted, as seen in Fig. 3, that a spring is mounted on the shaft 298, so that there is always a tension 20 tending to rotate said shaft and maintain said arm 301 in engagement with the co-acting cam member 302. As the shaft 299 is rotated, the arm 304 will be caused to turn on its pivot and since this arm is provided 25 near its outer end with a suitable knife member or severing blade, as the outer end of which arm 304 moves downwardly the stamp will be severed from the strip and on the further movement of said arm the presser member 308, which is pivotally mounted on the 30 rod 306 carried by the bracket 305, will press the stamp firmly against the envelop. The envelop has now been sealed and stamped and is ready to be discharged from the 35 machine.

Means for discharging the envelops from the machine.—The shaft 266 has also mounted thereon a sleeve 327 on which is mounted a cam block 326, said cam member 326 being provided with the release face 328 with which a cam member 329 coacts, so that as the shaft 266 is rotated the shaft 330 to which said cam member 329 is secured will be rocked and the upper end of the arm 322 45 carried by said shaft 330 will engage one end of the envelop and cause the same to be passed or thrown out of the machine in a very positive and effective manner, it being noted that the cam member 329 is always 50 maintained in operative relation with respect to the cam block 326 owing to the provision of the spring 333 mounted on the shaft 330.

I wish to call special attention to the manner in which different parts of the machine may be adjusted. The machine may be adapted for envelopes of different widths owing to the provision of the adjusting screws 78, as clearly indicated in Figs. 1 and 5. The amount of travel which is given to the table 19 may be adjusted as desired by adjusting the lever 8 in the slot 12 of the link 10. The moistening device for the roller 92 may be rendered inoperative by actuating 65 the handle 136 mounted on the shaft 135

and since the link 232 is connected at one end to the plate 235 and is removably connected at its other end to the arm 227, the liquid container 133 may be readily removed when desired. The container 248 may be 70 laterally adjusted as desired owing to the provision of the slot 244 in the plate or bar 235 and the manner in which said container is secured with respect to said slot. The stamp feeding rollers may be rendered inoperative when desired by actuating the lever 291 and thus raise the engaging portion 292 of the upper shaft 287 out of engagement with the lower feed roller or shaft 278, as will be apparent. The stamping mechanism 75 may be laterally adjusted owing to the provision of the slot 282 in the support 280 and the fastening device 284 carried by the depending arm 283, which is secured to the table 279 which carries the stamping mechanism. 80

It will now be apparent that the different operations hereinbefore described will be simultaneously carried out and that the envelop is automatically fed and directed from 90 one mechanism to the next in order, so that a number of envelopes are being operated upon at the same time. It will be further apparent that if desired the stamping and stamp feeding mechanism may not be 95 employed and the machine used for simply sealing the envelopes. It will also be apparent that by varying the gearing of the machine and employing gears having a greater or lesser number of teeth that the 100 time at which the respective operations are carried out may be varied accordingly.

It will now be apparent from the foregoing that I have produced a novel and useful construction of an envelop sealing and 105 stamp affixing machine which embodies the features of advantage enumerated as desirable in the statement of invention and the above description and while I have in the present instance shown and described the 110 preferred embodiment thereof which has been found in practice to give satisfactory and reliable results, it will be obvious that various changes may be made therein without departing from the spirit and scope of 115 my invention or sacrificing any of its advantages.

Having thus described my invention, what I claim as new and desire to secure by Letters Patent, is:—

1. In an organized machine for sealing and stamping envelopes, a driving shaft, an envelop feeding mechanism actuated thereby, a flap moistening mechanism actuated by said driving shaft, flap opening mechanism actuated by said driving shaft, means for maintaining the envelop stationary for a predetermined period, a directing mechanism with which the envelopes engage after leaving the flap moistening mechanism, means for bend- 125 130 135

ing the flap of the envelops, sealing rollers actuated by said driving shaft, means actuated by said driving shaft to feed the envelops to said rollers, means for moistening the stamp receiving portion of the envelops, means for feeding stamps to said portion, a stamping mechanism for severing the stamp and pressing the same against the envelop, and a discharge mechanism for removing the sealed and stamped envelop from the machine.

2. In an organized machine for sealing and stamping envelops, an envelop feeding mechanism, flap opening mechanism, flap moistening mechanism, a sealing device for the envelop, a driving shaft adapted to actuate said mechanisms and said device, a moistening device for the stamp receiving portion of the envelop located in proximity to said sealing rollers and beneath which the envelops are fed, means for automatically raising and lowering said device, and means for raising the envelop as it passes beneath said device.

3. In an organized machine for sealing and stamping envelops, envelop feeding mechanism, movable flap opening mechanism independent of the feeding means, flap moistening mechanism, sealing rollers, means for feeding the envelops from said flap moistening mechanism to said sealing rollers, means for moistening the stamp receiving portion of the envelop, a driving shaft, and means actuated thereby for severing and placing a stamp in position on the envelop.

35 4. In an organized machine for sealing and stamping envelops, a driving shaft, a shaft intermittently rotated thereby, a cam member carried by said last named shaft, an arm engaging said cam, a stamp severing and pressing mechanism actuated by said arm, and means for feeding an envelop beneath said stamp severing and pressing mechanism.

5. In an organized machine for sealing and stamping envelops, a driving shaft, a shaft intermittently rotated thereby, a cam member mounted on said shaft, a stamp severing and pressing device actuated by said cam, means for feeding an envelop beneath said stamp severing and pressing device, and means for discharging the envelop from the machine.

6. In an organized machine for sealing and stamping envelops, a driving shaft, a shaft intermittently rotated thereby, a cam member mounted on said shaft, a stamp severing and pressing device actuated by said cam member, means for feeding an envelop beneath said stamp severing and pressing device, a gear mounted on said intermittently rotated shaft, a second gear coacting therewith, and feed rollers for the stamps actuated by said second gear.

7. In an organized machine for sealing and stamping envelops, a driving shaft, a shaft intermittently rotated thereby, a cam mem-

ber mounted on said shaft, a stamp severing and pressing device actuated by said member, means for feeding an envelop beneath said stamp severing and pressing device, a gear mounted on said intermittently rotated shaft, a second gear coacting therewith, feed rollers for the same actuated by said second gear, and means for rendering said stamp feeding rollers inoperative.

8. In an organized machine for sealing and stamping envelops, a driving shaft, a shaft intermittently rotated thereby, a cam member carried by said shaft and having a release face, a lever engaging said cam, and means actuated thereby for discharging the envelops from the machine.

9. In an organized machine for sealing and stamping envelops, envelop feeding mechanism, a flap opening device, means for moistening the flap of the envelop, a driving shaft, sealing rollers actuated thereby, a second shaft intermittently rotated by said driving shaft, a cam member mounted on said intermittently rotated shaft and provided with a release face, a lever coacting with said cam member, and means actuated by said lever for advancing an envelop into position to be stamped after the same passes through said sealing rollers.

10. In an organized machine for sealing and stamping envelops, a driving shaft, sealing rollers actuated thereby, a second shaft intermittently rotated by said driving shaft, a stamping device actuated by said second shaft, and means actuated by said second shaft for advancing the envelop from said sealing rollers beneath said stamping mechanism.

11. In an organized machine for sealing and stamping envelops, a driving shaft, sealing rollers actuated thereby, a second shaft intermittently rotated by said driving shaft, a stamping device actuated by said second shaft, means actuated by said second shaft for advancing the envelop from said sealing rollers beneath said stamping mechanism, and means for discharging the envelop from beneath said stamping mechanism.

12. In an organized machine for sealing and stamping envelops, means for intermittently feeding an envelop into the machine, a flap opening device, means for guiding the envelops to said device, means for moistening the flap of the envelop, means for sealing the envelops, means for moistening the stamp receiving portion of the envelop, a stamping device to which the envelops are fed from said sealing means, means for feeding the stamps into operative position with respect to said stamping device, and mechanism for discharging the sealed and stamped envelops from the machine.

13. In an organized machine for sealing and stamping envelops, means for intermittently feeding the envelops thereto, a flap

- opening device, means for directing the envelops thereto, a moistening mechanism for the envelop flap, a driving shaft, a rock shaft, means intermediate said driving shaft and said rock shaft for actuating the latter, flap closing mechanism, a second rock shaft adapted to be actuated by said driving shaft, feeding means carried by said second rock shaft, sealing rollers operatively connected with said driving shaft to which the envelops are fed, a moistening device for the stamp receiving portion of the envelop and located in proximity to said sealing rollers, means actuated by said driving shaft for raising and lowering said moistening device, and a stamping mechanism also actuated by said driving shaft.
14. In an organized machine for sealing and stamping envelops, a driving shaft, a gear carried thereby, a second gear adapted to be actuated by said first gear, a rack arm carried by said second gear, a second shaft, a pinion loosely mounted thereon, a block secured to said pinion, a pawl carried by said block, a casing fixed on said second shaft and having a shoulder on its inner periphery with which said pawl coacts to intermittently rotate said second shaft, and a stamping mechanism actuated by said second shaft.
15. In an organized machine for sealing and stamping envelops, a driving shaft, a gear carried thereby, a second gear operatively connected with said first gear, a rack arm carried by said second gear, a second shaft, means carried thereby and coacting with said rack arm to intermittently rotate said second shaft, and stamp feeding mechanism adapted to be actuated by said second shaft.
16. In an organized machine for sealing and stamping envelops, a driving shaft, a gear carried thereby, a second gear operatively connected with said first gear, a rack arm carried by said second gear, a second shaft, means carried thereby and coacting with said rack arm to intermittently rotate said second shaft, stamp feeding mechanism adapted to be actuated by said second shaft, and means for rendering said stamp feeding mechanism inoperative.
17. In an organized machine for sealing and stamping envelops, a driving shaft, a gear carried thereby, a second gear operatively connected with said first gear, a rack arm carried by said second gear, a second shaft, means carried thereby and coacting with said rack arm to intermittently rotate said second shaft, stamp feeding mechanism adapted to be actuated by said second shaft, and stamping mechanism actuated by said second shaft.
18. In an organized machine for sealing and stamping envelops, a driving shaft, a gear carried thereby, a second gear operatively connected with said first gear, a rack arm carried by said second gear, a second shaft, means carried thereby and coacting with said rack arm to intermittently rotate said second shaft, stamp feeding mechanism adapted to be actuated by said second shaft, stamping mechanism actuated by said shaft, and means for discharging the envelops from the machine.
19. In an organized machine for sealing and stamping envelops, envelop feeding mechanism, movable flap opening mechanism, flap moistening mechanism independent of the feeding mechanism, sealing mechanism, driving means for said mechanisms, means for moistening the stamp receiving portion of the envelop, stamp feeding means, and stamping mechanism for severing and pressing a stamp against an envelop.
20. In an organized machine for sealing and stamping envelops, envelop feeding mechanism, movable flap opening mechanism, flap moistening mechanism independent of the feeding mechanism, sealing mechanism, driving means for said mechanisms, means for moistening the stamp receiving portion of the envelop, stamp feeding means, stamping mechanism for severing and pressing a stamp against an envelop, and devices for discharging the stamped envelop from the machine.
